UNITED STATES PATENT OFFICE.

FREDERICK H. EINWAECHTER, JR., AND FRANK A. CARDEGNA, OF BALTIMORE,
MARYLAND.

JOURNAL BOX.

Application filed October 16, 1923. Serial No. 668,891.

To all whom it may concern:

Be it known that we, FREDERICK H. EINWAECHTER, Jr., and FRANK A. CARDEGNA, citizens of the United States, residing at 5 Baltimore, in the State of Maryland, have invented certain new and useful Improvements in Journal Boxes; and we do hereby declare the following to be a full, clear, and exact description of the invention, such as 10 will enable others skilled in the art to which it appertains to make and use the same.

The invention relates to journal boxes primarily designed for use on locomotives.

One of the principal objects of the invention is to provide a journal box and lubrication cellar of comparatively simple construction having means for effectively retaining the cellar in position within the box under service conditions, thereby reducing to a minimum 15 the loss of the cellar and the resulting hot journals and train delays. The split pins and bolts now in use are very difficult to apply and maintain in position, the inconvenience attending the application and 20 removal of the cellar causing considerable loss of time and annoyance.

Our invention which has been designed to overcome these and other difficulties now experienced, involves the production of a 25 journal box and lubrication cellar retaining means, said means forming a closure for the cellar recess or opening and comprising a relatively wide movable bar adapted to bridge the opposite pedestal portions 30 of the journal box and be detachably connected thereto. The bar is preferably pivoted to one of the pedestal portions of the box and adapted to be swung across the 35 cellar opening and be firmly but detachably connected to the other of said pedestal portions, thereby facilitating the rapid application and removal of the cellar as occasions 40 require.

Another object of the invention is to provide 45 a journal box and cellar construction in which a bottom member is provided for supporting the cellar, said bottom member being detachably connected to the box and forming a reliable supporting means for the cellar which latter, as the result of our present 50 construction, can be made of pressed metal of very light weight as compared to the cast

cellars now in use. The present arrangement of detachable bottom plate supporting the cellar does away with the necessity 55 of grooving the interior of the pedestal portions of the box and the forming of co-acting guide ribs on the cellar, and as a result, greatly lessens the cost of manufacture and reduces maintenance charges to a 60 minimum.

A further object of the invention is to provide a reliable means for retaining the cellar within the journal box and at the same time permit of its rapid application 65 and removal, said means being readily connected to the construction of journal boxes and cellars now in use at comparatively small expense.

With these and other objects in view, the 70 invention consists in the combination, construction and arrangement of the several parts hereinafter described and pointed out in the claims.

In the drawings illustrating our invention:

Figure 1 is a view in end elevation of an engine journal box, lubrication cellar and retaining means therefor constructed in accordance with the invention. 80

Figure 2 is a vertical longitudinal sectional view on the line 2—2 of Figure 1.

Figure 3 is a horizontal sectional view on the line 3—3 of Figure 1.

Figure 4 is a detail horizontal sectional view on the line 4—4 of Figure 1. 85

Figure 5 is a fragmentary view in end elevation of our improved cellar retaining means applied to a journal box and cellar such as is now in use. 90

Figure 6 is a side elevation of the construction shown in Figure 5, a portion of said figure being broken away and shown in section.

Referring to the drawings in which similar reference characters designate corresponding parts in the several views, the journal box 1 comprises a top wall 2, and pedestal side wall portions 3, the interior of the box being indicated generally by the numeral 4 and designed to receive the journal and brass shown in dot and dash lines, and the cellar 5. 95

The bottom of the journal box consists of a plate member 6 preferably of wrought metal 100

capable of being economically blanked and shaped to form a reliable bottom closure upon which the cellar is supported. The plate is preferably shaped to conform to the bottom of the cellar and is provided at opposite side edges with lateral extensions 7 adapted to be received in grooves 8 at one end of the journal box, and lateral extensions 9 designed to fit within grooves 10 at the opposite end of the box. The respective grooves 8 and 10 are disposed in horizontal alignment so as to easily effect the insertion of the plate, said grooves being located near the bottom of the opposite side walls of the box forming the pedestal guide portions. The pedestal guide portions of the journal box are relatively spaced apart as best shown in Figure 3, the respective grooves in said portions acting to receive the respective spaced projections of the bottom plate. The relative spacing of the projections and their co-acting grooves permits of the removal of the plate upon the partial withdrawal thereof, it being obvious that as soon as the respective projections 7 and 9 pass out of the grooves that said plate can be readily lowered from the journal box. In a reverse manner, the plate may be readily inserted when assembling the structure about the journal.

The outer end of the plate 6 is provided with projecting portions 11 forming continuations of the lateral extensions 9, said projecting portions each having an edge 12 providing a shoulder designed to contact an adjacent end portion of the journal box and limit the inward movement of the plate when positioned in the box. The projecting portions 11 are each provided with an opening 13 through which passes the means connecting the cellar retaining device to the journal box.

The cellar retaining means includes a movable bar member 14 preferably formed of relatively wide and flat material, one end of which is bent to form a sleeve portion 15 adapted to receive a pivot pin, and the other end of which is maintained flat for contacting an adjacent end portion of one of the journal box side walls. The sleeve portion of the bar is pivotally mounted upon a bolt or pin 16 extending between the spaced lugs 17 projecting from the end portion of the opposite side wall of the box. In the embodiment of the invention shown in Figures 1 to 4, the bolt 16 is provided with a head 18 resting upon the upper lug 17, and a nut 19 positioned upon the threaded extension thereof projecting beneath the lowermost lug 17. As shown in Figure 1, the sleeve portion of the bar rests upon the lowermost lug which, together with the lowermost of the co-acting lugs 20 projecting from the end portion of the opposite side wall of the box, provides a reliable supporting means for

the bar 14 which in our present disclosure is of a construction sufficiently large to provide a very substantial end wall closure for the open end of the journal box through which the cellar is inserted.

The lugs 20 are relatively spaced one above the other so as to receive between them the free end of the pivoted bar 14, said free end being detachably retained in position by means of the pin 21 designed to pass through aligned openings in the lugs. The pin is provided with a head 22 adapted to engage the uppermost of the lugs 20, the end of the shank of said pin being formed with an opening designed to receive a suitable locking device, such as the split key 23, thereby preventing the accidental displacement of the pin and loss of the cellar.

In effecting the removal of the cellar, the locking device or key is removed and the pin 21 withdrawn, whereupon the bar can be swung upon its pivot and the cellar removed. When effecting the application of the lubricating means to the journals, the cellar is positioned within the recess or opening formed between the opposite side walls of the journal box and bottom plate 6, said cellar being slid thereinto across the end of the journal box in contact with the bar 14 which is forced into position beneath the journal until the free end of said bar moves between the lugs 20 and engages the adjacent portion of the journal box. The retaining pin 21 is now inserted through the aligned openings in the lugs and the locking device applied to insure its retention under most severe service conditions.

The bolt 16 forming the pivot for the bar member 14 and the pin 21 which maintains the member in closed position are both designed to pass through the openings 13 provided in the projecting portions of the bottom plate 6. The openings 13 are disposed in alignment with the openings formed in the respective lugs 17 and 20 so as to effect rapid assembling and detachment of the several parts. The nut 19 and locking key 23 are connected respectively to the bolt and pin beneath the projecting portions 11 of the plate 6, the upper surface of said projecting portions being slightly spaced from the underface of the bottom lugs 17 and 20, respectively. As the result of this construction it will be observed that the means pivotally mounting and retaining the closure member also serve to reliably connect the bottom wall or plate to the journal box.

In the manufacture of the journal box the respective lugs 17 and 20 are preferably formed of wrought metal, said lugs being of U-shape and positioned in the mold for rigid union with the metal when poured to form the cast journal box. Such a construction provides a very durable lug which can not be easily broken as the result of service con-

ditions and which is firmly anchored in the cast metal so as to resist all strains to which it may be subjected.

The lubricating cellar 5 is of a shape which can be readily formed from pressed metal, one wall thereof having connected thereto an extension 25 designed to limit the movement of the cellar when being inserted through the open end of the box, said extension also facilitating the removal of the cellar. The extension may be a separate piece suitably riveted to the cellar, as shown at 26, or it may be otherwise formed to provide a convenient limiting and gripping means. The elimination of the projecting guide ribs on the cellar and the co-acting grooves on the journal box in the embodiment of our invention above described, reduces the cost of manufacture and also does away with those portions of the structure subjected to wear and necessitating replacement.

Referring to Figures 5 and 6, there is illustrated a modified construction of the invention applicable to journal boxes and cellars now in use. The end portions of the opposite side walls of the journal box are suitably drilled and tapped to receive the threaded ends of eye bolts 27, said eye bolts forming lugs adapted to support the cellar retaining bar 28. The bar 28 is preferably bifurcated at each end, the forked portion thereof being designed to straddle the lugs, as shown. Pins 29 pass through aligned openings in the forked portions, said pins also entering the registering openings provided in the lugs or eye bolts 27 so as to permit of the pivoting of the bar upon at least one side of the journal box, when one of the pins is removed. In detaching the cellar one of the pins is withdrawn whereupon the bar 28 is swung about the other of the pins which acts as a pivot, in which position the cellar can now be easily removed. The application of the cellar to the journal box involves the reverse operation, as will be obvious.

A cellar retaining means constructed in accordance with our invention is very easy to manipulate and insure a most reliable lubrication of the journals in that the loss of the cellar, as the result of service conditions, is reduced to a minimum. The disadvantages of train delays and costs of replacement resulting from this loss is obviated by the present invention. Our improved journal box and lubrication cellar also possesses advantages of construction facilitating assembling and detachment of the parts, the utilization of the means connecting the retaining bar to the journal box as a means for maintaining the bottom wall of the journal box in position and connected thereto, affording a very simple and effective construction.

We claim:

1. The combination with a journal box, of a lubricant cellar mounted therein, and means including a member pivotally mounted upon the end portion of one side wall of the journal box and adapted to be swung across said cellar and connected to an adjacent end portion of the other journal box side wall for retaining the cellar in position within the journal box, and supporting means for said cellar slidably inserted therebeneath. 70 75

2. The combination with a journal box having an open end, of a cellar mounted in said journal box and insertible through said open end, means including a member designed for movement across said open end for retaining the cellar within the journal box, supporting means for said cellar, and means detachably securing the aforesaid retaining means, when moved to closed position across the open end of the box, and also said supporting means. 80 85

3. The combination with a journal box having an open end, of a cellar mounted in said journal box and insertible through said open end, a closure member for said open end having one end thereof connected to the journal box and the other end adapted to be moved across said open end thereof, and means connecting the relatively free end of said member to the journal box for maintaining the cellar in position therein and independent plate means supporting said cellar. 90 95 100

4. The combination with a journal box having an open end, of a cellar mounted therein and insertible through said open end, supporting means for said cellar, a pivoted closure member for the open end of the journal box adapted to be positioned adjacent the cellar for retaining the same in position within the journal box, and means for maintaining said closure member adjacent the cellar, said means also cooperating with said supporting means. 105 110

5. The combination with a journal box, of a cellar mounted therein, and means for retaining said cellar in position, said means including a projection provided on the journal box, a retaining bar having at least one end formed with an opening, a pin passing through said opening and projection for pivotally connecting the retaining member thereto, another projection pivoted on the journal having an opening therein, a pin adapted to pass through said opening and designed to maintain the opposite end of the retaining member against an adjacent portion of the journal box, and a key adapted to be connected to said last named pin for preventing its accidental displacement, and a supporting plate positioned beneath said cellar and retained in position by the same pin. 115 120 125 130

6. The combination with a journal box, a cellar formed with side and bottom walls detachably mounted therein, said journal box having a detachable bottom adapted to support said cellar beneath its bottom wall, and pivotal means for retaining the cellar in position within the journal box. 50
7. The combination with a journal box having an open end, of a cellar formed with 10 side and bottom walls insertible through said open end, a detachable supporting plate for said cellar beneath its bottom wall, said supporting plate being connected to the journal box and a pivoted member retaining said cellar in position. 15
8. The combination with a journal box having an open end, of a cellar insertible therein, a detachable bottom wall for the journal box adapted to support said cellar, 20 said bottom wall being insertible from the open end of the box and common means for retaining both cellar and bottom wall in position. 25
9. The combination with a journal box having an open end, of a cellar insertible therein, a detachable bottom wall slidably inserted beneath the cellar in the journal box from the open end thereof, said bottom wall being adapted to support the cellar, 30 and means for retaining said cellar in position upon the bottom wall. 35
10. The combination with a journal box, of a cellar mounted therein, a detachable supporting member for said cellar, a movable member adapted to maintain the cellar in position upon said supporting member, and means detachably connecting at least one end of said movable member to the journal box, said means being connected to the 40 supporting member. 45
11. The combination with a journal box, of a cellar mounted therein, a detachable plate slidably mounted in the journal box for supporting said cellar, a movable member having at least one end thereof pivoted to said journal box whereby the opposite

end thereof may be moved into position for retaining the cellar, and means detachably connecting the free end of said member to an adjacent portion of the journal box, said last named means being connected to the 55 slideable plate for maintaining the same in position. 60

12. The combination with a journal box having opposite open ends, of a cellar with 55 side and bottom walls insertible through one of said open ends, a supporting member for said cellar, means detachably connecting said supporting member to the journal box at one end thereof, means provided on said 60 cellar adapted to engage the supporting member for limiting its movement when being inserted in the journal box, and pivotal means for retaining the cellar in position within the journal box. 65

13. The combination with a journal box having spaced pedestal guide portions upon each side thereof, of a cellar, a detachable plate supporting said cellar, said plate having spaced projections adapted to engage 70 adjacent portions of the spaced pedestal guides and being removable therefrom upon the partial withdrawal of said plate, and means detachably connecting said plate to the journal box. 75

14. The combination with a cast metal journal box, of a cellar formed with side and bottom walls mounted therein, and means for retaining said cellar in position, said means including a wrought metal projection united with the journal box when cast, a closure member having one end pivotally connected to said wrought metal projection, a similar projection formed in said box, means detachably connecting the other 80 end of said closure member to the last named projection, and a plate beneath said 85 cellar for supporting the same.

In testimony whereof we affix our signatures.

FREDERICK H. EINWAECHTER, Jr.

FRANK A. CARDEGNA.
